US0D1071790S

(12) **United States Design Patent** (10) Patent No.: **US D1,071,790 S**
(45) Date of Patent: ** Apr. 22, 2025

(54) **BUCKLE**

(71) Applicant: **YKK Corporation**, Tokyo (JP)

(72) Inventor: **Asahiko Sakai**, Toyama (JP)

(73) Assignee: **YKK Corporation**, Tokyo (JP)

(**) Term: **15 Years**

(21) Appl. No.: **29/890,127**

(22) Filed: **Apr. 20, 2023**

(30) **Foreign Application Priority Data**

Nov. 30, 2022 (JP) ..... 2022-025861 D

(51) **LOC (15) Cl.** **02-07**

(52) **U.S. Cl.**

USPC **D11/216**

(58) **Field of Classification Search**

Assistant Examiner — Sara Michie Pottenger

(74) Attorney, Agent, or Firm — Kilpatrick Townsend & Stockton LLP

(57) **CLAIM**

The ornamental design for a buckle as shown and described.

DESCRIPTION

FIG. 1 is a first perspective view of a buckle showing my new design;

FIG. 2 is a second perspective view thereof;

FIG. 3 is a third perspective view thereof;

FIG. 4 is a fourth perspective view thereof;

FIG. 5 is a front view thereof;

FIG. 6 is a rear view thereof;

FIG. 7 is a top view thereof;

FIG. 8 is a bottom view thereof;

FIG. 9 is a left side view thereof; and,

FIG. 10 is a right side view thereof.

The broken lines in the drawings are for the purpose of illustrating portions of the buckle that form no part of the claimed design.

The dot-dashed lines which define the bounds of the claimed design form no part of the claimed design.

1 Claim, 10 Drawing Sheets
